UNITED STATES PATENT OFFICE

EDWARD C. ANGELL, OF NEW YORK, N. Y.

APPARATUS FOR FILLING CONTAINERS

Application filed September 21, 1926. Serial No. 136,806.

The present invention relates to a method and apparatus for automatically filling containers from a tank with fluid or other material, and which containers are automatically advanced to be registered with the fillers.

This invention has for its object to provide a method and apparatus that will automatically discharge fluid from a number of fillers connected with a supply tank into a series of containers, whereby upon the containers being intermittently advanced to register with the fillers respectively in succession, each container will receive a small fixed or constant fractional amount of fluid from each filler, so that the final portion received will cause the container to be filled with the proper desired amount.

A further object of the invention is to provide an apparatus of this character that will discharge the fixed small fractional portions into containers placed below the same, without engagement with the container, so that containers of flexible material such as paper or the like can be used.

Another object of the invention is to provide in an apparatus of this character, an arrangement of the fillers distributed throughout the tank, as from one end to the other, whereby each container as advanced to cooperate with the successive fillers, will receive a portion from each part of the tank, so that if the character of the fluid varies at different portions of the tank, the containers as filled will each have substantially uniform quantity of the fluid.

In the accompanying drawings showing one embodiment of my invention,

Figure 1 is a plan view partly in section.

Fig. 2 is a front elevation.

Fig. 3 shows an end view enlarged partly in section.

Fig. 4 shows enlarged one of the filling means.

Fig. 5 shows a portion of the conveyor and the means for holding the containers.

As shown in the drawings one form of apparatus for carrying out my invention comprises a base or table 1 mounted on suitable legs 2. At one end of the apparatus is located a filling tank 3, on standards 4, 5. This

as shown is of elongated form, and at the bottom is provided with a series of extension chambers 6, twelve of which are shown arranged preferably in a line, see Figs. 1 and 2. Each of these chambers is provided with a suitable liquid delivering means operated from a main driving shaft to each deliver a fixed predetermined quantity of liquid from the tank 3, that may be milk or other desired fluid. One form of such device is shown in Figs. 3 and 4 in which a tube 7 projects up from the bottom of the chamber, and a cup 8 slides on this tube by its lower neck 9, with suitable packing 10 where it engages the pipe. The pipe 7 has its upper open end located in the tank, and this tank receives fluid whose level is maintained below the top of these pipes 7. The cup 8 is moved up and down by suitable means, and when its open top is submerged it will fill with the fluid. When the cup is raised it will carry this amount of fluid above the upper end of the pipe 7. This will permit the contents to flow down through this pipe until the top of pipe 7 reaches the point 11 in the neck, so that the contents of the cup will be delivered through the pipe 7, but no further quantity until the operation is repeated. This series of cups is operated in unison from a main shaft 12 at the rear of the machine, that rotates in bearing 13, 13, driven by suitable means such as a motor 14, through suitable gearing 15, and a chain 16 running on a sprocket 17 on the shaft 12. A shaft 18 mounted in the standards 4 is driven from the shaft 12 by gears 19 and 20. In the tank is mounted a shaft 21 projecting at each end to receive crank arms 22, that connect with rods 23, that engage cranks 24 on shaft 18. On the shaft 21 are a series of crank arms 25, with forked ends each connecting by links 26 with one of the cups 8. By this means the cups are moved up and down from the main shaft, and each will deliver its capacity of fluid through its individual outlet pipe 7.

These twelve filling devices are designed to cooperate with twelve containers that may conveniently be carried by an endless belt or chain 27, extending the length of the machine and carried around sprockets 28 and

29. The latter is advanced intermittently whereby to move the container holders 30 on the chain a unit distance, whereby each holder will advance the distance apart of the 5 tubes 7 of the filling devices. The chain is arranged so that the holders 30 will bring twelve of the containers thereon successively beneath the twelve filling tubes 7 respectively at each period of rest, and at each advance the 10 container will move to the next filling tube, or beyond at the last tube. Thus for twelve intermittent advance movements a container will be brought to filling position successively under each of the twelve filling tubes. The 15 cups are designed to contain one-twelfth of the desired contents of the containers. The first filling station will deliver one-twelfth of the container capacity, such as a pint or quart; then the container moves to the second 20 filling station, or tube, and there receives the second one-twelfth of a pint. At the twelfth advance, this container will receive the final one-twelfth, and thus be filled the desired amount. But it will be understood 25 that the containers are placed on the holders by the operator so that another container is brought under the first filling tube at each movement of the chain. It is obvious that a greater or less number of filling stations could 30 be provided, but where there are n filling tubes or stations, each will deliver the $1/n$ th part of the contents of the container. The holders 30, see Fig. 5, carried by the chain 27, are provided with angular clips 31 and 32, the 35 latter having a slot at its angular connection with the base, will be slightly yielding, and will engage with the bead on the bottom of the container. At the rear stops 33 may be provided, a container being slid across the 40 holders from the front until it strikes these stops by which it will be properly positioned on the holder.

The rear sprocket 29 is mounted on a cross shaft 34, see Fig. 1, actuated by a ratchet 45 wheel 35 thereon engaged by a pawl 36. The latter is carried by an arm 37 rocked from a cam 38 on a cross shaft 39. This shaft is turned by a gear 40 thereon engaging a gear 41 on the main shaft. A spring bolt 42 slides 50 in a bracket 43 and is operated by a cam 44 on shaft 39. This bolt engages a notched disk 45 on the cross shaft 34 after the pawl 36 has advanced this shaft the proper distance so that the sprocket 29 will advance the conveyor chain the distance of one holder, and serve to lock the chain at each stop.

The extensions 6 of the tank 3 are preferably provided with removable bottoms of suitable metal and as shown in Fig. 4 a disk 60 46 is removably attached to the open end of the extension by bolts 47. The disk has an opening 48 to receive a bushing 53 soldered to the tube 7. This bushing has a reduced threaded neck 51 and above this is a conical 65 shoulder 49 on the bushing to engage a coni-

cal seat 50 in the opening 48 in the disk 46. The bushing is placed as shown in Fig. 4 with the tube 7 projecting through it, and a nut 52 screws on the bushing and is turned up against the disk 46 to draw the bushing down 70 on the conical seat and form a tight joint. When it is desired to remove the contents of the extension 6, the nut 52 is removed and the bushing 53 can be moved upwardly with the tube 7.

It will be understood from the above description that each of the filling devices will discharge a fixed or constant predetermined charge or amount of fluid at its outlet pipe 7, and that this is absolutely independent of any engagement with the container. By this means containers of any desired character can be employed, such as the paper containers or bottles sometimes used for holding milk. The chain conveyer will simply bring these 80 bottles, that have a comparatively large or wide mouth, to rest just below the discharge tube 7, and the fluid will fall by gravity into the container. This will make the discharge of the fluid absolutely independent of the 85 form or capacity of the container.

It will be further observed that the twelve filling devices are distributed or arranged from one end of the fluid tank 3 to the other. Where certain fluids such as milk are used, the 90 character varies at times and a greater proportion of the butter fats or cream may exist at one portion of the tank than at another portion. Unless the fluid is agitated, the portion discharged by one filler might vary in its 95 character from that discharged by another filler at a remote position. But by the present invention each container will receive a portion taken from the tank at different locations from one end to the other, which will 100 provide a uniform character of the fluid in all 105 of the containers.

Another great advantage of this fractional or multiple filling from relatively small fractional amounts resides in the fact that where the container is entirely filled at one operation, there is a strong tendency to foam by air bubbles being produced, and this would cause the contents of the receptacle to overflow as first filled, and when the foam subsides there would be less than the required quantity of fluid in the container. By the present invention a very small fraction of the quantity is inserted at each advance of the conveyer and such objection is avoided.

In machines of the character set forth it is customary to have the conveyer advance the filled containers to a suitable closing or sealing device, that is a part of the apparatus, and which will automatically cause each filled bottle as advanced to be closed, or closed and sealed. Where paper containers of the kind indicated are employed such a container is collapsed or pressed together at the top, and thereupon a sealing strip, such as bent metal 110 115 120 125 130

is applied to the closed lips to seal the container. In the present apparatus the conveyer is shown as continued to a sealing mechanism. Here suitable arms or jaws will collapse the container and a sealing strip of metal of angular form may be placed by hand or otherwise over the closed lips, and thereupon the jaws 55 and 56 will press together the sealing strip and seal the bottle.

10 It will be understood that this sealing means completes one operation at each advance of the conveyer, so that as each filled bottle goes beyond the last filler it will be sealed, at this station. Where a bottle is 15 filled at each rest period, and a previously filled bottle is sealed, the filling operation must be effected in the same time that the sealing operation is done. But with the present invention only one-twelfth of the capacity of 20 the container is discharged into each container as each filled container is sealed, for the reasons that 12 containers on the conveyer are each receiving simultaneously one-twelfth of the capacity. By this means the operation is 25 to be effected very rapidly, yet the filling operation will avoid the disadvantages just set forth.

What I claim is:

1. In an apparatus for filling liquid into 30 containers, a source of liquid supply, a series of liquid measuring and delivering elements communicating with said source, means for intermittently operating said series of elements as a unit, and means for sequentially 35 positioning a plurality of containers to receive liquid from said elements, whereby each container receives a measured increment of liquid from each element, whose aggregate for the series is an accurate total of the de- 40 sired amount.

2. In an apparatus for filling liquid into 45 containers, a series of liquid measuring devices, a common source of liquid supply for said devices, means for intermittently operating said series of devices to simultaneously 50 deliver a measured quantity of liquid to a series of containers, and an intermittently operated conveyor for sequentially positioning a series of containers to receive liquid from 55 said devices in timed relation with the operation of said devices, whereby each container receives a measured increment of liquid from each device, whose aggregate for the series is an accurate total of the desired amount.

3. In an apparatus for filling liquid into 60 containers, a tank, a series of liquid measuring devices therein each having independent discharge pipes, means for intermittently operating said series of devices as a unit, and a conveyor for sequentially positioning a series of containers to receive liquid from said devices in timed relation with the operation of said devices, whereby each container re- 65 ceives a measured increment of liquid from

each device, whose aggregate for the series is an accurate total of the desired amount.

4. In an apparatus for filling liquid into 70 containers, a source of liquid supply, a series of liquid measuring and delivering elements arranged to each deliver a fixed predetermined quantity of liquid from said source, means for sequentially presenting a series of containers in position to receive the liquid from said delivering elements respectively, 75 and means for simultaneously operating all said delivering elements alternately with the said sequential presenting of the containers in receiving position, whereby each container will receive a measured increment of liquid from each element in succession and the aggregate quantity received in each container will be the same desired quantity of the fluid.

5. The method of filling containers, which 80 consists in independently discharging from separate points in a common source of supply into each of a series of containers a measured fractional portion of the total quantity desired in the container, intermittently advancing said series of containers to further 85 independent fractional fillings from said source until the last of the series has received a sufficient number of fractions to complete the whole.

6. The method of filling containers, which 90 consists in independently discharging from separate points in a common source of supply into each of a series of containers a measured fractional portion of the total quantity desired in the container, intermittently advancing said series of containers to further 95 independent fractional fillings from said source until the last of the series has received a sufficient number of fractions to complete the whole, and adding an unfilled container at 100 each advancement, whereby the new container receives the first fractional filling as the last container in the series receives its final fractional filling.

7. The method of filling liquid containers 110 from a common source of supply, which consists in intermittently feeding measured fractional quantities to the same container at different places of discharge from said source, whereby any inequalities in the liquid at the various points of discharge will be equalized 115 in all containers so filled when the total number of fractional fillings has reached the whole.

Signed at New York city, N. Y., on Sept. 14, 120 1926.

EDWARD C. ANGELL.
